UNITED STATES PATENT OFFICE

137,612

DESIGN FOR A MOTOR OPERATED FLUID PUMP AND DISTRIBUTING DEVICE

Robert Flanagan, Glen Rock, and Myron L. Taylor, Ridgewood, N. J., assignors to Bendix Aviation Corporation, South Bend, Ind., a corporation of Delaware

Application September 5, 1942, Serial No. 108,146

Term of patent 14 years

(Cl. D26—5)

To all whom it may concern:

Be it known that we, Robert Flanagan and Myron L. Taylor, citizens of the United States, residing in Glen Rock and Ridgewood, respectively, both in the county of Bergen and State of New Jersey, have invented a new, original, and ornamental Design for a Motor Operated Fluid Pump and Distributing Device, of which the following is a specification, reference being had to the accompanying drawings, forming part thereof.

In the drawings:

Fig. 1 is a plan view of a motor operated fluid pump and distributing device showing our new design.

Fig. 2 is a side elevational view of the same unit.

Fig. 3 is an end elevational view of the same unit; and

Fig. 4 is an elevational view of the end opposite that illustrated in Fig. 3.

The characteristic features of our design reside in the portions shown in full lines in the drawings.

We claim:

The ornamental design for a motor operated fluid pump and distributing device, as shown and described.

ROBERT FLANAGAN.
MYRON L. TAYLOR.
